UNITED STATES PATENT OFFICE

104,262

DESIGN FOR A CLOSURE CAP

Alanson B. Hewes, New York, N. Y., assignor to Victor Metal Products Corporation, Brooklyn,
N. Y., a corporation of New York

Application March 5, 1937, Serial No. 68,020

Term of patent 7 years

To all whom it may concern:

Be it known that I, Alanson B. Hewes, a citizen of the United States, residing in the Borough of Manhattan, city, county, and State of New York, have invented a new, original, and ornamental Design for a Closure Cap, of which the following is a specification, reference being had to the accompanying drawing, forming part thereof.

The figure is a perspective view of a closure cap showing my new design.

I claim:

The ornamental design for a closure cap, substantially as shown.

ALANSON B. HEWES.
